(57) **CLAIM**

We claim the ornamental design for a panel cover, as shown and described.

DESCRIPTION

FIG. 1 is a perspective view of a panel cover of a first embodiment as installed on an instrument panel having user operated buttons;

FIG. 2 is a perspective view of the front of the panel cover of FIG. 1;

FIG. 3 is a perspective view of the rear of the panel cover of FIG. 1;

FIG. 4 is a front view of the panel cover of FIG. 1;

FIG. 5 is a rear view of the panel cover of FIG. 1;

FIG. 6 is a top view of the panel cover of FIG. 1;

FIG. 7 is a bottom view of the panel cover of FIG. 1;

FIG. 8 is a left side view of the panel cover of FIG. 1;

FIG. 9 is a right side view of the panel cover of FIG. 1;

FIG. 10 is a perspective view of a panel cover of a second embodiment as installed on an instrument panel having user operated buttons;

FIG. 11 is a perspective view of the front of the panel cover of FIG. 11;

FIG. 12 is a perspective view of the rear of the panel cover of FIG. 11;

FIG. 13 is a front view of the panel cover of FIG. 11;

FIG. 14 is a rear view of the panel cover of FIG. 11;

FIG. 15 is a top view of the panel cover of FIG. 11;

FIG. 16 is a bottom view of the panel cover of FIG. 11;

FIG. 17 is a left side view of the panel cover of FIG. 11; and,

FIG. 18 is a right side view of the panel cover of FIG. 11. The portions of the Figures shown in broken lines are not part of the claimed design and are for illustration only.

1 Claim, 8 Drawing Sheets
